UNITED STATES PATENT OFFICE.

HARRY R. MUMMA, OF ROCKFORD, ILLINOIS, ASSIGNOR TO BURSON KNITTING COMPANY, OF ROCKFORD, ILLINOIS, A CORPORATION OF ILLINOIS.

DESIGN FOR A STOCKING.

Application filed March 14, 1922. Serial No. 1,163. Term of patent 14 years.

To all whom it may concern:

Be it known that I, HARRY R. MUMMA, a citizen of the United States, residing at Rockford, in the county of Winnebago and State of Illinois, have invented a new, original, and ornamental Design for Stocking, of which the following is a specification, reference being had to the accompanying drawing, forming a part thereof.

In the drawing,—

Figure 1 is a rear view of a stocking fashioned in the knitting, shown on a shaped leg form. The longitudinally lined portions follow the wales. These lined por-

tions represent a structural demarcation in the fabric from the intermediate portions B. In the example shown the wales in the portions A are knit closer than the wales in the portions B, thereby producing the ribbed effect.

Fig. 2 is a side view of a stocking embodying my new design, shown on a shaped leg form.

I claim:

The ornamental design for a stocking, as shown.

HARRY R. MUMMA.
